UNITED STATES PATENT OFFICE.

SIMEON C. LAWLOR, OF DULUTH, MINNESOTA.

MOP-HEAD AND IMPLEMENT CLAMP.

No. 819,895.

Specification of Letters Patent.

Patented May 8, 1906.

Application filed October 4, 1904. Serial No. 227,093.

To all whom it may concern:

Be it known that I, SIMEON C. LAWLOR, a citizen of the United States, residing at Duluth, in the county of St. Louis and State of Minnesota, have invented certain new and useful Improvements in Mop-Head and Implement Clamps; and I do hereby declare the following to be a full, clear, and exact description of the invention, such as will enable others skilled in the art to which it appertains to make and use the same.

My invention relates to mop-head and implement clamps, and has for its object the provision of a clamp adapted to hold a mop or brush or scraper.

With this and other objects in view it consists of the constructions, combinations, and arrangements of parts hereinafter described and claimed.

In the drawings, Figure 1 is a plan view of said clamp. Fig. 2 is a perspective view of said clamp opened to receive a suitable brush. Fig. 3 is a side elevation of said clamp, and Fig. 4 is a front sectional elevation of the upper jaw of said clamp in open position.

In the drawings, 1 is a handle portion forked at one end, as at 2, and provided at the ends of the tines of the forked portion with radially-corrugated or ribbed cheeks 3.

Each of said cheeks is centrally apertured for the passage of a bolt 4. Secured to said forked portion is a jaw 5, provided with rearwardly-extending radially-corrugated or ribbed ears 5^a, adapted to overlap said cheeks

and in operation engage therewith. Said ears are centrally apertured for the passage of said bolt. The outer face of said jaw preferably has strengthening-ribs 5^b formed thereon and is apertured for the passage of a

locking-bolt 6, which bolt is curved to correspond approximately to the arc in which the apertured portion of the jaw will travel when said jaw is opened from a closed position. One end of said bolt 6 is fastened in any suit-

able manner and at a suitable point to a second jaw 7, provided with rearwardly-extending ears 7^a, adapted to overlap said ears 5^a. Said ears 7^a are centrally apertured for the passage of a thimble or sleeve 8, surrounding

the shank of said bolt 4 for a portion of its

length. The outer face of said jaw 7 preferably has strengthening-ribs 7^b formed thereon. Formed upon the inner face of said jaw 7, a short distance back from the forward edge thereof, are a suitable number of spurs 9, adapted to form back-stops for certain implements which may be inserted in said clamp and to operate as teeth to grip larger implements which may be inserted in said clamp. The opposite said jaws preferably have relatively opposite bends formed therein, as at 5^c and 7^c, respectively, and other but shorter such bends 5^d and 7^d, respectively, nearer their forward edges, whereby said clamp is better adapted to grasp the implements inserted therein. Upon one end of said bolt 4 is mounted a wing-nut 4^a, whereby said bolt may be set to draw said cheeks and ears 5^a into facial engagement with each other to maintain the jaw 5 at a predetermined angle 7^c with respect to said ferrule. A winged nut 6 is mounted on the free end of said bolt 6, whereby said jaws may be closed and locked upon such mop or implement as it may be desired to clamp therein. Mounted upon said 75 thimble or sleeve 8 is a coiled spring 10, one end of which bears against the inner face of one of said jaws and the other end of which bears against the inner face of the other of said jaws, whereby said jaws are forced open 80 when said nut 6^a is unscrewed or loosened.

Having now described my invention, what I claim, and desire to secure by Letters Patent, is—

1. In a mop-head and implement clamp, 85 the combination of a forked handle portion, two jaws pivotally secured to the tines of said forked portion, locking means adapted to secure one of said jaws at a predetermined angle to said handle portion, a bolt secured to 90 one of said jaws and extending through an aperture formed in the other of said jaws, at an angle to the pivotal axis thereof, and adjustable retaining means engaging said bolt and adapted to retain said jaws thereon and 95 to lengthen or contract the space on said bolt available for the occupancy of said jaws, substantially as described.

2. In a mop-head and implement clamp, 100 the combination of a forked handle portion,

two jaws pivotally connected therewith, means for adjustably securing one of said jaws in a rigid position with relation to said handle portion, a bolt secured to one of said 5 jaws and extending through the other said jaw in a plane at an angle to the plane of the pivotal axis of said jaws, a nut adapted in co-operation with said bolt to close said jaws

and to secure said jaws in a closed position, substantially as described.

In witness whereof I hereunto affix my signature in presence of two witnesses.

SIMEON C. LAWLOR.

Witnesses:

JAMES T. WATSON,

WELLINGTON M. BLEWETT.
